UNITED STATES PATENT OFFICE.

THOMAS JOSEPH STURTEVANT, OF WELLESLEY, MASSACHUSETTS, ASSIGNOR TO STURTEVANT MILL COMPANY, A CORPORATION OF MAINE.

MIXING-MACHINE.

1,122,660.

Specification of Letters Patent.

Patented Dec. 29, 1914.

Application filed April 20, 1914. Serial No. 833,148.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Mixing-Machines, of which the following is a specification, reference being had therein to the accompanying 10 drawing.

This invention relates to certain improvements in the so-called "Hunso" mixer or mixing machine covered by U. S. Patent No. 985,299, dated Feb. 28, 1911, and has 15 for its object to provide convenient means for discharging the mixed material, as well as to improve the efficiency of the machine, and to avoid objectionable friction which results from the construction hereinbefore 20 in use, and in which some of the material leaks out between the rotating drum and the surrounding stationary housing, so that it scrapes around between the drum and housing, causing more or less friction.

25 In carrying the present invention into effect the rotating drum is provided with a series of openings closed by swinging doors which, when the means for holding them closed is released, will open by gravity for 30 the discharge of the material as the openings and doors approach the lower side of the drum in its rotation, and will also be closed by gravity as the openings and their doors move upward, such gravity-closing 35 being preferably assisted by means which will force the doors tightly to closed positions if their weight is not sufficient to effect this result.

In the accompanying drawing Figure 1 is 40 a sectional view of a mixer embodying the present invention, and Figs. 2 and 3 are detail views showing one of the swinging doors and related parts illustrated in Fig. 1.

45 Referring to the drawing, 19 denotes a rotatable drum or cylinder which will be suitably mounted and driven, as will be understood from Patent No. 985,299 above referred to.

50 Surrounding the central portion of the rotatable drum or cylinder 19 is a casing 24 properly supported on a frame or base 12 and open at its bottom for the discharge of the mixed material. The said rotating drum or cylinder is provided at its middle

portion, within the casing 24, with openings 55 25 normally closed by swinging doors 26.

The rotating drum or cylinder 19 is provided internally at its opposite end parts with a series of inclined wings 44 fixed to the lifting flanges or buckets 45, these inclined blades 44 serving to force the material toward the central or middle part of the drum where the openings 25 are located, as in the machine of Patent No. 985,299 hereinbefore referred to, so that the material within the drum may be readily discharged, when desired, through the openings at the middle portion of the drum.

The swinging doors 26 are locked in closed positions by means of spring-pressed 70 hooked catches 46 engaging bars 47 on said doors, the said hooked catches 46 being yieldingly held in locked positions by means of plate springs 48 bearing against tail portions 49 on the said catches. Two catches 75 for each door, one near each end of the drum 19, are preferably provided, as will be understood from Fig. 3. A single circular series of catches, one for each door, may, however, be employed, if desired.

80 When it is desired to open the doors 26 for the discharge of material a roller or rollers 50, controlled by a manually operated lever 51, may be moved from the position shown in dotted lines to the position 85 shown in full lines in Fig. 1; and when in this releasing position the outer ends of the hooked catches 46 will engage said roller or rollers on the descending side of the rotating drum so as to release the catches and 90 thus permit the swinging doors to open by gravity. When two hooked catches 46 are employed for each door 26 the two rollers for releasing said catches may be mounted on a fork 52 actuated by the lever 51. As 95 the swinging doors move upward with the ascending side of the rotating drum they will naturally close by gravity; but to insure that the doors will be tightly closed, should this not be done by gravity alone, a 100 closing roller 53 carried by a spring-pressed lever 54 is preferably provided, said roller being in a position to engage ribs 55 on the backs of the swinging doors 26.

105 From the foregoing it will be understood that after the mixing operation has been completed and it is desired to discharge the mixed material, the attendant, by means of

the lever 51, moves the releasing roller or rollers to the position shown in full lines in Fig. 1 so that the outer ends of the spring-pressed hooked catches 46 will engage the said roller or rollers and will be unlatched, thus permitting the doors to be opened by gravity for the discharge of the material.

The improved machine is more especially intended for use in mixing fertilizers, but 10 may be used for other purposes, as will be understood.

While it is preferred to employ spring-pressed catches for holding the swinging doors in closed position, it will be understood 15 that other forms of catches might be employed for this purpose.

Having thus described my invention I claim and desire to secure by Letters Patent:

- 20 1. A rotatable mixing drum provided with circumferential discharge openings, combined with swinging doors to close said openings, said doors being adapted to be opened and closed by gravity, spring-pressed catches for holding said doors in closed position, and manually adjustable means adapted to be moved into position to cause the said catches to be released when it is desired that the said doors should open.
- 25 2. A rotatable mixing drum provided with circumferential discharge openings, combined with swinging doors to close said openings, said doors being adapted to be opened and closed by gravity, spring-pressed catches for holding said doors in closed position, manually adjustable means adapted to be moved into position to cause the said catches to be released when it is desired that the said doors should open,
- 30 3. A rotatable mixing drum provided with circumferential discharge openings, combined with swinging doors to close said openings, said doors being adapted to be opened and closed by gravity, spring-pressed catches for holding said doors in closed position, manually adjustable means adapted to be moved into position to cause the said catches to be released when it is desired that the said doors should open,
- 35 4. A rotatable mixing drum provided with circumferential discharge openings, combined with swinging doors to close said openings, said doors being adapted to be opened and closed by gravity, spring-pressed catches for holding said doors in closed position, and means for forcing said doors to closed position in assisting the gravity-closing action.
- 40 5. A rotatable mixing drum provided with circumferential discharge openings, combined with swinging doors to close said openings, said doors being adapted to be opened and closed by gravity, spring-pressed catches for holding said doors in closed position, manually adjustable means adapted to be moved into position to cause the said catches to be released when it is desired that the said doors should open.
- 45 6. A rotatable mixing drum provided with circumferential discharge openings, combined with swinging doors to close said openings, said doors being adapted to be opened and closed by gravity, catches for holding said doors in closed position, and manually adjustable means adapted to be moved into position to cause the said catches to be released when it is desired that the said doors should open.
- 50 7. A rotatable mixing drum provided with circumferential discharge openings, combined with swinging doors to close said openings, said doors being adapted to be opened and closed by gravity, catches for holding said doors in closed position, and manually adjustable means adapted to be moved into position to cause the said catches to be released when it is desired that the said doors should open.

to be released when it is desired that the said doors should open, and a spring-pressed lever provided with a roller to act on said doors to force them to closed position in assisting the gravity-closing action. 55

4. A rotatable mixing drum provided with circumferential discharge openings, combined with swinging doors on said drum to close said openings, said doors being adapted to be opened and closed by gravity, 60 one or more series of spring-pressed catches for holding said doors in closed position, a roller or rollers movable into and out of the path of movement of the outer ends of said catches, and a manually controlled lever 65 by which said roller or rollers may be moved into a position to release one or more series of catches when it is desired that the said doors should open.

5. A rotatable mixing drum provided at 70 or near its middle portion with circumferential discharge openings, combined with swinging doors on said drum to close said openings, said doors being adapted to be opened and closed by gravity, one or more 75 series of spring-pressed catches for holding said doors in closed position, a roller or rollers movable into and out of the path of movement of the outer ends of said catches, and a manually controlled lever by 80 which said roller or rollers may be moved into a position to release one or more series of catches when it is desired that the said doors should open.

6. A rotatable mixing drum provided 85 with circumferential discharge openings, combined with swinging doors to close said openings, said doors being adapted to be opened and closed by gravity, catches for holding said doors in closed position, and manually adjustable means adapted to be moved into position to cause the said catches to be released when it is desired that the said doors should open. 90

In testimony whereof I affix my signature, 95 in presence of two witnesses.
